UNITED STATES PATENT OFFICE

118,113

DESIGN FOR A COLLAPSIBLE STAND-SUPPORTED BATH

Abraham G. Feldman, Chicago, Ill., assignor to Storkline Furniture Corporation, Chicago, Ill.,
a corporation of Illinois

Application January 20, 1939, Serial No. 82,458

Term of patent 7 years

To all whom it may concern:

Be it known that I, Abraham G. Feldman, a citizen of the United States, residing at Chicago, in the county of Cook and State of Illinois, have invented a new, original, and ornamental Design for a Collapsible Stand-Supported Bath, of which the following is a specification, reference being had to the accompanying drawings, forming part thereof.

Fig. 1 is a perspective view of the collapsible stand-supported bath as it appears when open and ready for use showing my new design;

Fig. 2 is a front elevational view of the same as it appears when collapsed;

Fig. 3 is a side elevational view of the same as it appears when collapsed; and

Fig. 4 is a perspective view similar to Fig. 1 but taken from directly in front.

I claim:

The ornamental design for a collapsible stand-supported bath, as shown and described.

ABRAHAM G. FELDMAN.
